WELDER'S CART

Marion L. Ewing and Orison P. Kambestad, Sacramento, Calif., assignors of one-third to Kambestad-Ewing, Inc., Sacramento County, Calif.

Application October 19, 1953, Serial No. 27,217

Term of patent 14 years

(Cl. D14—3)

To all whom it may concern:

Be it known that we, Marion L. Ewing and Orison P. Kambestad, citizens of the United States, residents of Sacramento, in the county of Sacramento and State of California, have invented a new, original, and ornamental Design for a Welder's Cart, of which the following is a specification, reference being had to the accompanying drawing, forming a part thereof, wherein the single figure is a perspective view of the welder's cart, showing our new design.

We claim:

The ornamental design for a welder's cart, substantially as shown.
